Frederick Hackmann

by Edward E. Longau, Atty.

UNITED STATES PATENT OFFICE.

FREDERICK HACHMANN, OF ST. LOUIS, MISSOURI, ASSIGNOR OF ONE-SIXTEENTH TO CHAUNCEY R. WATSON, ONE-SIXTEENTH TO PHILIP E. MOODY, AND ONE-SIXTEENTH TO ELIJAH E. FRASER, ALL OF DETROIT, MICHIGAN, AND THREE-EIGHTHS TO DAVID M. HUTCHINSON, OF FERGUSON, MISSOURI, AND ONE-FOURTH TO HERMAN C. STIFEL, OF ST. LOUIS, MISSOURI.

SPARK-PLUG.

1,357,975.

Specification of Letters Patent. Patented Nov. 9, 1920.

Application filed June 26, 1919. Serial No. 306,835.

To all whom it may concern

Be it known that I, FREDERICK HACHMANN, a citizen of the United States, and resident of the city of St. Louis and State of Missouri, have invented certain new and useful Improvements in Spark-Plugs, of which the following is a specification containing a full, clear, and exact description, references being had to accompanying drawings, forming a part thereof.

This invention relates to spark plugs and has for its primary object a spark plug which is provided with an auxiliary spark gap, so that the electric discharge will be intensified.

A further object is to provide a spark plug having a porcelain insulator which is divided into three parts and a binding nut swivelly secured between two of the porcelain insulators.

In the drawings:

Figure 1 is a vertical section of my complete device.

Fig. 2 an enlarged sectional view of the binding nut and the insulators.

Fig. 3 is a sectional view of one of the insulators.

Fig. 4 is a sectional view of another portion of the insulator.

Fig. 5 is a side elevation of the binding nut.

In the construction of my device I provide a casing 6, which is of the usual type, having its lower end threaded as indicated by the numeral 7, and its upper end provided with a hexagonal or wrench-engaging surface 8. The lower end of the casing 6 is provided with a bore 9, in which an aluminum sleeve 10 is secured. This sleeve 10 is provided with an electrode 11. The casing 6 is further provided with a projecting shoulder 12, the shoulder 12 serving as a rest for the gasket 13, and on this gasket is placed the insulator 14. Secured within the insulator 14 is placed the electrode 15, this electrode being securely baked in the insulator. The upper portion of the casing 6 is provided with a bore 16, a portion of which is screw-threaded as indicated by the numeral 17, and within the bore 16 the insulator 14 is inserted. The screw thread portion 17 of the bore 16 receives the pack-

ing nut 18, so that the member 19 of the insulator 20 may be secured and pressed downward toward the insulator 14.

Between the insulators 14 and 19 I insert the gasket 21, which is composed of heat-resisting resilient material and which will prevent any leakage of gas. The insulator 20 is composed of the sections 19 and 22, the portion 19 being provided with conical recesses 23 and 24, these recesses being formed on opposite ends thereof and separated from each other by means of a partition wall 25. This partition wall is provided with an opening 26, through which the primary electrode 27 is inserted. This electrode is provided at one end with a conical or ball-shaped head 28 and on its other end with screw threads 29, over which the securing wrench 30 and the binding nut 31 are screwed. The insulator 22 is provided with a conical projection 32, which fits securely within the recess 24 formed in the insulator 19, and with a mushroom-shaped flange 33, which projects over a portion of the binding nut 18. This insulator is provided on its upper surface with a circular recess 33, in which the insulator washer 34 is placed, this insulating washer surrounding the electrode 27 and is interposed between the nut 30 and the insulator 22, the object of this being to prevent leakage. The nut 18 is provided on its upper edge with a flange 35, which flange enters the recessed or under-cut portion 36 of the insulator 22.

When it is desired to assemble my device the nut 18 is inserted between the insulators 19 and 22, the electrode 28 then passed through the opening 26 and the opening 37 formed in the insulators, the packing 34 slipped over the electrode and the nut 30 tightened, thus securely holding the insulators 19 and 22 together and at the same time loosely securing the binding nut 18 between the two insulators. With this construction it is possible, by merely removing the nut 18 from the spark plug, to keep that portion of the plug intact. This is not possible in the structure of present devices, as when a spark plug is constructed with a narrow gap, it is virtually composed of 4 parts, being the binding nut, the casing and two portions of the insulator.

Another advantage of my device is that an ordinary wrench can be used in securing same to a gasoline engine, or in fact a socket wrench may be employed.

5 It will be observed that the recess 23 in addition to forming a receptacle for receiving the conical or ball shaped head 28 also acts as a primary spark chamber when the insulators 14 and 19 are secured together.

10 It will further be noted that the aluminum sleeve 10 has a higher specific heat than the iron or steel shell 7 surrounding it and will attain a higher temperature than said shell and with the consequent tendency to reduce

15 the greasy carbon deposit to a dry powder which will readily drop off the spark plug and pass out through the exhaust manifold without fouling the spark plug or short circuiting it.

20 Having fully described my invention, my claim is:

1. A spark plug comprising a casing, an insulator provided with an electrode mounted in said casing, an aluminum sleeve surrounding the lower end of said insulator and spaced apart therefrom, an electrode secured

25 to said aluminum sleeve, an insulator provided in its upper and lower ends with a recess mounted in said casing and above the first mentioned insulator, a packing nut for securing said insulators together within said casing, a third insulator mounted within the recess formed in the upper end of the second mentioned insulator and projecting over and

30 arranged to shield the packing nut, an electrode provided with a conical head extending through said last mentioned insulators, said electrode being provided with screw threads on its upper end, a nut for securing the second and last mentioned insulators together, and a binding nut mounted on the upper end of said electrode.

35 2. A spark plug provided with an air gap comprising a casing, screw-threaded at its lower end, its upper end being provided with a wrench engaging surface, a circular bore formed in both ends of the casing, said bores being of different diameter, so as to form a shoulder between them, a counter bore

40 formed in one of the circular bores, an aluminum sleeve located in said counter bore, an electrode secured within the end of said aluminum sleeve, a gasket located on the shoulder, an insulator located on the gasket,

45 an electrode carried by the insulator, a second insulator superimposed on the first mentioned insulator and spaced apart therefrom, a gasket for separating said insulators, a

third insulator secured to the second mentioned insulator, an electrode extending 50 through the last mentioned insulators, a binding nut for securing said insulators together, and a packing nut interposed between the last mentioned insulators, surrounding the same and adapted to be inserted 65 within the casing, and means located on last mentioned electrode to establish electrical connection between it and a suitable source of supply.

3. A spark plug comprising a casing, an 70 upper and lower porcelain insulator mounted in said casing, the upper insulator being provided with a recess which forms a spark gap chamber between said insulators, a nut mounted in the casing for securing said insulators together within the casing, an electrode provided with a conical sparking point mounted in the upper insulator, an electrode mounted in the lower insulator, an aluminum sleeve mounted in the casing and surrounding 80 the lower insulator and spaced apart therefrom, and a grounded electrode carried by the aluminum sleeve.

4. A spark plug comprising a casing, a lower porcelain insulator mounted in said 85 casing, an upper insulator composed of two sections, one of which is provided in its lower end with a recess forming a spark chamber, a nut for securing the lower insulator and one of the sections of the upper insulator together, a flange formed on one of the sections of the upper insulator and projecting beyond the circumference of said

90 nut, an electrode mounted through both sections of the upper insulator, said electrode being provided with a conical head located in the recess formed in one of the sections of the upper insulator, a nut mounted on the electrode for securing both sections of the upper insulator together, a packing mounted 95 on the electrode between said nut and the upper section of the upper insulator, an electrode mounted in the lower insulator and projecting beyond both ends thereof, an aluminum sleeve located in the lower end of 100 the casing and spaced apart and surrounding the lower end of the lower insulator, and a grounded electrode carried by the lower end of the spark plug.

In testimony whereof, I have signed my 110 name to this specification, in presence of two subscribing witnesses.

FREDERICK HACHMANN.
